SAFETY DEVICE FOR LOCKS

Henry Alberg, Millstadt, Ill.

Application March 6, 1930, Serial No. 433,674
Renewed March 2, 1933

12 Claims. (Cl. 70—8)

The invention relates to key-hole guards and particularly to an improved guard for completely blocking and covering the key opening in a door or the like.

5 An object of the invention is to provide a device of the character referred to adapted for insertion into the key-hole of a lock to prevent manipulation of the latch bolt.

Another object of the invention is to provide 10 an improved key-hole guard having novel retaining means for insuring its retention in place over and in a key-hole, and means for preventing unauthorized disengagement of said retaining means.

15 Another object of the invention is to provide an improved key-hole guard which is simple to operate and inexpensive to manufacture.

The foregoing and such other objects of the 20 invention as will appear hereinafter as the description proceeds will be more readily understood from a perusal of the following specification, reference being had to the accompanying drawing, in which:

Fig. 1 is a perspective view of the improved 25 key-hole guard.

Fig. 2 is a fragmentary vertical sectional view 30 through a door showing the device in section thereon.

Fig. 3 is a front elevational view showing the 35 device in locked position.

Fig. 4 is a sectional elevational view taken on line 4—4 of Fig. 2.

Fig. 5 is a view similar to Fig. 4, taken on line 45 5—5 of Fig. 2.

Fig. 6 is a perspective view of the retaining pin.

Fig. 7 is a side elevational view partly in section, showing a modified form of the device.

Fig. 8 is a view similar to Fig. 7 showing an 50 other modification.

The device generally comprises a suitable plate, adapted to be placed over the key-hole in a door, having an integral extension adapted to extend into the key-hole to prevent insertion of a key into the lock from the side of the door opposite to that side in which the device is inserted; and suitable means for securely retaining and locking said device in place.

Referring to the drawing, the key-hole guard, 55 shown in Figs. 1 to 6 inclusive, preferably comprises a substantially rectangular body portion or closure plate 11 having a suitable extension 12 preferably formed integral therewith and extending outwardly at right angles therefrom. The extension 12 is preferably formed in cross

section to conform substantially to the shape of the key-hole 13 in the lock housing 14, as shown in Fig. 2. A boss 15, countersunk or recessed to receive the reduced portion 16 of a hand grip 17, extends outwardly from the plate 11 in a direction opposite to that of the extension 12. The reduced portion 16 is also countersunk as at 18 and a pin or stem 19 is secured therein, adjacent one of its ends, in any suitable manner. The retaining pin or stem 19 has an elongated head 21, forming oppositely disposed wings 22, on its free end, and it extends through an opening in plate 11, as shown. A compression spring 23, inserted in the countersunk portion 18 of sleeve 16, normally urges the elongated head 21 against plate 11.

The hand grip 17 and the pin 19 provide means for retaining the device in place over the key-hole. To mount the device in place, the elongated head 21 is positioned in vertical alignment with extension 12. The extension is inserted into the key-hole 13 bringing the plate 11 tightly against one of the lock finishing or cover plates 24 on the door 25. The hand grip 17 then is urged inwardly, compressing spring 23, and partially rotated to move the wing portions 22 on pin 19 into engagement with the rear side of one of the cover plates 24, as shown in Figs. 2 and 5. The hand grip 17 is spaced a suitable distance from the boss 15 to adapt the improved key-hole guard for mounting over key-holes in doors having cover plates of various thicknesses.

Suitable means are provided on the rotatable hand grip 17 to prevent its being turned to disengage the elongated head 21 by the application of a key or tool through the key-hole from the outside of the door. To this end, a latch 26 is pivotally mounted between ears 27 on the hand grip 17, adapted for engagement between a pair of spaced lugs 28, preferably formed integral with plate 11, when the means for retaining the device in place is in engagement with the cover plate 24. To insure alignment of the device with the key-hole, an aligning pin 29 is provided on the same side of plate 11 as and below the extension 12, which pin extends into the key opening 31 in one of the cover plates 24. To remove the device from the door the latch 26 is moved out of engagement with lugs 28 and the hand grip 17 is turned to disengage the retaining pin 19 from the cover plate. The device is then free to be withdrawn from the key-hole.

If desirable, locking means such as shown in Fig. 7, at 32, may be employed. In this embodiment of the invention the locking means or latch

- 32 is provided with a projection or offset 33 adapted to engage in a recess 34 provided in the closure plate 11a. The retaining pin 19a is provided with an elongated head 21a, as previously described, and in this particular instance the inwardly disposed edges 35 of said head are inclined or beveled to automatically urge upon rotation, the retaining means inwardly against the action of the spring.
- 10 10 In Fig. 8, yielding means in the form of a leaf spring 36 is provided on the hand grip 17a to automatically engage in the recess 34a in plate 11 when the device is locked in place.
- 15 It can be readily understood that the closure plate 11, of the improved key-hole guard, covers the entire key opening 31 in one of the cover plates 24, thus obstructing vision through the key-hole; and the extension member 12, conforming substantially to the shape of the key-hole, prevents access being had to the latch bolt 37 or to the retaining pin 19 from the side of the door opposite to that in which the device is inserted.
- 20 25 Although exemplary forms of the invention have been illustrated in the accompanying drawing and described in detail in the foregoing specification, it is to be understood that the device is capable of incorporating various modifications in detail structure without departing from the spirit of the invention or the scope of the appended claims.
- I claim:
1. A device of the character described adapted to be mounted over the key opening in a door having a lock therein, comprising; a closure plate; an integral extension on said plate adapted to extend through the key-hole in said lock, yieldably mounted rotatable retaining means carried by said plate; said retaining means being adapted 35 to engage the cover plate on said door to retain the device in place, and positive locking means on the retaining means cooperating with the closure plate to prevent unauthorized manipulation of said retaining means.
- 40 45 2. A device of the character described adapted to be mounted over the key opening in a door having a key operated lock, comprising in combination; a closure plate; an extension formed integral with and extended outwardly at right angles from one side of said closure plate; a boss on the other side of said plate; retaining means mounted in said boss, and retaining means extending through said plate and being adapted to engage behind the cover plate of the lock to retain the device in place.
- 50 55 3. A device of the character described, comprising in combination; a closure plate; an extension formed integral with and extending at right angles from one side of said closure plate; a pin, having an elongated head, mounted in said plate; the head of said pin being disposed on the side of the plate carrying said extension; a boss on the other side of said plate through which said pin extends; a collar secured on the end of said pin, and a spring interposed between said collar and the boss to normally urge the elongated head into contact with said closure plate.
- 60 65 4. A device of the character described adapted for insertion into the key-hole of a door lock having cover plates associated therewith, comprising in combination; a closure plate; an extension formed integral with and extending at right angles from one side of said closure plate; a boss on the other side of said plate; retaining means mounted in said boss; said retaining

means extending through said closure plate and being adapted to engage one of the cover plates to retain the device in place, and means for locking said retaining means to prevent unauthorized manipulation thereof.

5 80 85 90 95 100 105 110 115 120 125 130 135 140 145 150 A device of the character described adapted for insertion into the key-hole of a door lock having cover plates associated therewith, comprising in combination; a closure plate; an extension formed integral with and extending at right angles from one side of said closure plate; a boss on the other side of said plate; retaining means mounted in said boss; said retaining means extending through said closure plate and being adapted to engage behind one of said cover plates to retain the device in place thereover, and manually operable pivotally mounted means for locking said retaining means in engagement with the cover plate.

6 100 105 110 115 120 125 130 135 140 145 150 A device of the character described comprising, in combination, a closure plate, an extension formed integral with said closure plate; a pin, having an elongated head, mounted in said plate, the head of said pin being disposed on the side of the plate carrying said extension, a boss on the other side of said plate through which said pin extends, a collar secured on the end of said pin, and a spring interposed between said collar and the boss to urge normally the elongated head into contact with said closure plate.

7 110 115 120 125 130 135 140 145 150 A device of the character described comprising, in combination, a closure plate, an extension formed integral with said closure plate, a pin, having a head, mounted in said plate, the head of said pin being disposed on the side of the plate carrying said extension, a boss on said plate through which said pin extends, a collar secured on the end of said pin, and a spring interposed between said collar and the boss to urge normally the head into contact with said closure plate.

8 120 125 130 135 140 145 150 A device of the character described comprising, in combination, a closure plate, an extension formed integral with and extending at right angles from one side of said closure plate, a pin, having an elongated head, mounted in said plate, the head of said pin being disposed on the side of the plate carrying said extension, a collar secured on the other end of said pin, and a spring interposed between said collar and the boss to urge normally the head into contact with said closure plate.

9 130 135 140 145 150 A device of the character described comprising, in combination, a closure plate, an extension formed integral with said closure plate, a pin, having a head, mounted in said plate, the head of said pin being disposed on the side of the plate carrying said extension, a collar secured on the other end of said pin, and a spring interposed between said collar and the boss to urge normally the head into contact with said closure plate.

10 140 145 150 A device of the character described adapted to be mounted over the key opening in a door having a key operated lock, comprising, in combination, a closure plate, an extension formed integral with and extended from one side of said closure plate, a boss on the other side of said plate, retaining means mounted in said boss and extending through said plate adapted to engage behind the cover plate of the lock to retain the device in place.

11 150 A device of the character described adapted for insertion into the key-hole of a door lock having cover plates associated therewith, com-

prising, in combination, a closure plate, an extension formed integral with and extending from one side of said closure plate, retaining means mounted in said plate, said retaining means extending through said closure plate and being adapted to engage one of the cover plates to retain the device in place, and means for locking said retaining means to prevent manipulation thereof.

10. 12. A device of the character described adapted for insertion into the key-hole of a door lock

having cover plates associated therewith, comprising, in combination, a closure plate, an extension formed integral with said closure plate, retaining means mounted in said plate, said retaining means extending through said closure plate and being adapted to engage behind one of said cover plates to retain the device in place thereover, and manually operable pivotally mounted means for locking said retaining means in engagement with the cover plate.
